[57] CLAIM

The ornamental design for a cart, as shown and described.

DESCRIPTION

FIG. 1 is a top plan view of a cart showing my new design;

FIG. 2 is a bottom plan view thereof;

FIG. 3 is a right side elevational view thereof;

FIG. 4 is a front elevational view thereof;

FIG. 5 is a rear elevational view thereof;

FIG. 6 is a left side elevational view thereof;

FIG. 7 is a top perspective view thereof, the wheels removed and a portion of the side wall of the cart shown broken away for clarity of illustration; and

FIG. 8 is a bottom perspective view thereof, with the wheels removed.

FIG. 1
